UNITED STATES PATENT OFFICE.

OTIS W. YOUNG, OF CHICAGO, ILLINOIS, ASSIGNOR TO THE PYLE-NATIONAL COMPANY, OF CHICAGO, ILLINOIS, A CORPORATION OF NEW JERSEY.

LOCOMOTIVE VALVE GEAR.

Application filed September 17, 1921. Serial No. 501,377.

My invention relates primarily to valve and reversing gears for steam engines and has particular reference to a gear for use with the well-known type of railroad locomotive which is driven by two steam engines, one on either side of the main frame, and it has for some of its objects to provide means for making the piston of one engine provide the lap and lead movement for itself and the valve travel for the other engine and vice versa and has for other objects to provide a light and durable mechanism, one in which very long valve travel without undue angularity can be had and in which a minimum number of changeable or other variable parts appear. Still other objects will appear as the description proceeds.

It is illustrated more or less diagrammatically in the accompanying drawings, wherein:

Figure 1 is a perspective diagrammatic view,

Figure 2 is a detailed view with parts in section of the concentric shafts,

Figure 3 is a detailed view of the radius bar,

Figure 4 is a detailed view of the reverse shaft,

Figures 5 and 6 are details.

All parts are indicated by like letters throughout the several drawings. Since my invention is primarily applied to locomotives, I have illustrated it diagrammatically so applied, but in so illustrating it, I have omitted all working parts and details of the locomotive which are not directly concerned with the operation of my invention, since the application of the parts herein illustrated will be clear to any one instructed in the locomotive art.

A are cross-head guides in which reciprocate the cross heads A', which transmit their impulse by the shafts A² to driving wheels, not herein shown. Connected to the cross-heads are the piston rods A³ which carry the pistons A⁴, reciprocating in the usual engine cylinders, not herein illustrated.

B is a steam chest piston valve, diagrammatically illustrated and adapted to reciprocate in a steam chest of the usual type, not herein illustrated. B' are valve rods, pivoted to links B² B³, B² is in turn pivoted

to the floating lap and lead lever B⁴, while B³ is pivoted to a similar lever B⁵.

Pivoted to the cross-heads A' are floating links C, the outer ends of which are pivoted to the lower extensions C' of the reversing links C², which are rotatably mounted as at C³ on the locomotive frame, not herein shown. Pivoted to the upper ends of the reversing links are the combination links or reach rods C⁴, the opposite ends of which are pivotally secured to the upper ends of the floating levers B⁴, and B⁵ respectively.

D is a solid shaft extending across the locomotive frame and rotatably mounted thereon in any suitable way. Removably secured to its opposite ends are the upwardly extending cranks D' and D². Pivoted to the upper end of D' is the radius bar D³, which extends through the reversing link C² and is forked as at D⁴ and may carry the usual link block, not herein illustrated. The outer extension D⁵ is adapted to penetrate and be secured to the radius bar lifter block D⁶ whose connection with the reversing gear will later be described. Pivoted to the crank D² on the opposite end of the shaft D is a floating lever B⁵, earlier described.

Rotatably mounted on the shaft D and concentric with it is the hollow shaft E having the bearings E' and the sleeves E², from which project the crank arms E³ and E⁴. On E³ is pivoted the floating link B⁴ which in turn is pivoted to the link or reach rod C⁴ and thus to the reversing link C². Pivoted on the crank arm E⁴ is the radius bar D⁷ identical with the bar D³ and similarly engaging a reversing link C², and provided with a radius bar lifter block D⁶. The projecting ends of the shaft D serve as supporting bearings for both shafts.

F is a reversing shaft on which is pivoted a reversing bar F', the lower arm of which F², has pivoted to it a reach rod F³, the opposite end of which is pivoted in a yoke F⁴ and pivoted to the reversing lever F⁵. The upper arm F⁶ terminates in a fork F⁷ the arms of which engage the sides of the radius bar lifter block D⁶ and are suitably pivoted thereto. Keyed to the reversing shaft F is the crank arm F⁸, adjacent to the reversing bar F'. Keyed to the opposite end of the shaft F is the arm F¹⁰, forked as at F¹¹, rotatably to engage the radius bar lifter block D⁶ in which is secured the outer end

of the radius bar D^7 . Pivoted to the arm F^8 is the reach rod F^{12} , the opposite end of which is pivoted to the yoke F^4 .

It will be evident that while I have shown 5 in my drawings, an operative device, still many changes might be made in the size, shape, and arrangement of parts without departing from the spirit of my invention. I wish therefore, that my drawings be considered 10 as in a sense diagrammatic.

The use and operation of my invention are as follows:

It must first be understood that the valve movement for the two engines of the locomotive is obtained entirely from the piston movement of those two engines. The peculiarities of lap and lead in valve travel, are, of course, well known and need no particular discussion at this time. Suffice it to 15 say, that it is necessary to have two separate sources of power in order to provide the proper lap and lead and valve travel movement. In my arrangement, I make the reciprocation of the piston of each engine 20 give the lap and lead movement for its own valve and at the same time give the valve travel movement for the valve of the other engine. Thus it is necessary to connect 25 across between the two engines by any suitable means such as the two rock shafts shown.

Referring first to Fig. 1, when the piston reciprocates it will cause the reversing link to rock back and forth. The rocking of 30 this link will cause the floating lap and lead lever to reciprocate, and assuming for the instant that the arm on the hollow shaft which supports the floating lap and lead lever is fixed, the only movement given to 35 the engine valve on the right hand side will be the lap and lead movement caused by the rocking of the lap and lead lever. This movement is a very slight movement, as 40 may be seen by the arrangement of the lever. We have assumed that the lever on the hollow shaft upon which the lap and 45 lead lever on the right hand side is mounted is fixed.

Referring again to Fig. 1, we see that the 50 reversing gear has been manipulated to bring the radius bar block near the upper end of the slot in the reversing link. The engine on the other side will similarly have the block near the bottom of the reversing 55 link as it will be noted that the reversing mechanism is such that when one bar goes up the other goes down. In double cylinder engines the main rod connection to the driving wheels is in effect a crank on each end 60 of the driving axle, one crank on each end of the driving wheels is in effect a crank on each end of the driving axle, one crank 90° in advance of the other. Consequently one 65 engine, usually the right engine may be said to lead the other 90°. If, however, we

should consider the left hand engine as leading its lead would then be 270° instead of 90°. For this reason a valve deriving its entire movement from the reciprocation of the pistons must be arranged for valve 70 travel producing mechanism direct on one side and indirect on the other. This is the reason for causing one radius bar to go up when the other goes down. Now with the engine moving the reciprocation of the 75 cross-head will result in a rocking of the reversing lever and this rocking of the reversing lever will result in a rocking of the floating lap and lead lever and thus the valve on the right hand side will be given 80 this lap and lead movement owing to the rocking of the right hand reversing lever and the same will be true of the valve on the left hand side owing to the rocking of the left hand reversing lever. When the 85 two blocks are moved away from the center of the reversing levers, the radius bars will commence to reciprocate and the reciprocation of the radius bar will tend to rock the two concentric shafts which extend 90 across the engine. The rocking of the radius bar on the right hand side will result in a rocking of the lever which supports the lap and lead lever on the other side, that is to say, for the left hand engine, and the 95 left hand piston thus takes its lap and lead movement from its own piston but gets its valve travel from the reciprocation of the piston of the engine on the other side.

The reversing rod is so controlled by the 100 reversing lever that a pull on the lever to the left, as illustrated in Fig. 1, will depress the radius bar D^3 and raise the radius bar D^7 , since, of the two reach rods, one rotates the reversing bar arm which is 105 pivoted on the shaft, and thus depresses its outer end. The other rotates the reversing shaft in the opposite direction and thus lifts the crank arm on the outer end of the shaft and with it lifts the radius bar D^7 . 110

I claim:

In a duplex valve gear a reversing means comprising a single rotatable shaft extending from side to side of the mechanism, a lever fixed thereupon, a second lever rotatable thereupon, a valve operating element secured to each of said levers, an additional reversing lever rigidly secured to said rod and a reversing lever in rigid relation with the lever rotatably mounted on said rod, a connection between each of said last mentioned levers and an operating element, adapted, through said connections, simultaneously to rotate the valve operating levers in opposite directions. 115

Signed at Chicago, county of Cook and State of Illinois, this 9th day of September 1921.

OTIS W. YOUNG.
